UNITED STATES PATENT OFFICE.

ALBERT CEDERLUND, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

TENSION FOR LOOM SHUTTLES.

Application filed January 6, 1928. Serial No. 244,961.

This invention relates to improvements in tensioning mechanism for loom shuttles and it is the general object of the invention to provide a simplified self-threading eye for 5 automatic weft changing looms and operating to take up slack in the filling and at the same time provide proper tension for the weft.

In the weaving of certain fabrics such as 10 silk it is highly desirable that the weft tension be maintained uniformly inasmuch as the threads entering into the finished cloth are so small that variation in the tension is readily perceptible. When the weft is silk, either natural 15 or artificial, it is desirable to provide means for taking up any slack which may occur between the selvage and the shuttle when the loom beats up and it is an important object of my present invention to provide a self-threading shuttle having an improved means 20 for taking up a comparatively large amount of slack with a rather small motion on the part of the slack taking-up device.

It is a further object of my present invention to provide a tubular guide for a light plunger which has projecting from opposite sides thereof weft engaging horns which act to equalize the strain on the plunger so that the latter may move easily and without unnecessary friction in the tube.

It is another object of my present invention to combine with the tube a relatively fixed finger around which the weft is looped by the horns moving with the plunger.

With these and other objects in view which will appear as the description proceeds, my invention resides in the combination and arrangement of parts hereinafter described and set forth in the claims.

In the accompanying drawings wherein I have shown a convenient embodiment of my invention,

Fig. 1 is a top plan view of a shuttle having my invention applied thereto,

Fig. 2 is an enlarged top plan of the right hand end of Fig. 1 with certain parts in section and showing the parts in the position they assume during the second pick after transfer,

Fig. 3 is a view similar to Fig. 2 but with the parts moved to complete the threading operation,

Fig. 4 is an enlarged front elevation taken in the direction of arrow 4, Fig. 1,

Figs. 5 and 6 are vertical sections on lines 55 5—5 and 6—6, respectively, of Figs. 4 and 3, respectively, and

Fig. 7 is a vertical section similar to Fig. 5, but showing only the tubular guide for the sliding plunger.

It is to be understood that the shuttle set forth herein may be used in connection with an automatic weft replenishing loom wherein a full bobbin is inserted into the shuttle at the magazine end of the loom, the shuttle being picked across to the remote side of the loom to partly thread the shuttle. In looms of this type the shuttle is not ordinarily completely threaded until the shuttle is being picked back toward the magazine side of the loom on 70 the second pick following transfer. The shuttle S has the usual springs 10 which receive the rings 11 on the butt 12 of the bobbin B. The shuttle may be lined with fur as at 13 to prevent unwinding of the weft W in conical 75 layers. The shuttle is provided at the right hand end thereof as shown in Fig. 1 with an eye receiving chamber 14 and may have the end thereof provided with groove 15 in which the weft lies during the first pick after the 80 bobbin B is inserted into the shuttle S by transferring mechanism not shown.

The block E has front and rear walls 20 and 21, respectively, screws 22 passing through the shuttle and into the walls to hold the 85 block in the chamber 14. Projecting rearwardly and toward the adjacent end of the shuttle is a threading finger 23, the rearmost portion of which may extend beyond the rear part of groove 15 a slight amount as shown 90 in Figs. 2 and 3. The rear wall 21 may be provided with a second threading finger 24 which is spaced somewhat from the finger 23 as shown in Fig. 5 to define with the latter a slot 25 through which the weft W extends.

Extending upwardly from the bottom 26 of the eye is a post 27, see Fig. 5, spaced from the rear wall 21 to define a passage through which the thread passes. A tubular guide 30 may be formed as part of the bottom 26 100 and has a bore 31 which has extending therefrom for a portion of its length slots 32 through which project weft engaging horns 33 and 34, respectively. As shown in Figs. 4 and 6 said horns both extend upwardly a 105 short distance above the top of the tubular element 30 and are then inclined upwardly and to the right toward the threading finger

23. There is one horn on each side of the tube and said horns are both supported by a light plunger 35 which is freely movable in the bore 31. Said plunger is connected by 5 means of a light spring 36 to a lever 37 as at 38 and said lever is pivoted to a pin 39, being held normally to the right as shown in Fig. 3 by an elastic 40 which may be connected to the rearwardly extending arm 41 of the lever 10 37 and pass through a screw 42 extending vertically through the shuttle.

A threading arm 43 is secured to the tubular element 30 so as to lie between the horns 33 and 34 when the parts are in the position shown in Fig. 2, said arm being inclined in a direction opposite to that in which the upper portions of the horns 33 and 34 extend and having the upper surface thereof inclined sufficiently so that a thread may rise 20 therealong to pass to the left of said arm as viewed in Fig. 6.

When a transfer of bobbins is to take place in the shuttle the newly inserted bobbin B will be passed into the shuttle by transfer 25 mechanism not shown and the end T of the weft W wound on the bobbin will extend to the right as shown in Fig. 1, lying in the groove 15. On the first pick after transfer the thread will continue to assume the position shown in Figs. 1 and 4, but on the return 30 pick when the shuttle is again moved toward the replenishing side of the loom the thread T will pass down a slot 50 defined between the finger 23 and the bottom of the groove 35 15 and will pass into a slot 51 formed in the wall 20 of the eye. The thread is thus moved downwardly and will extend behind and slip below the bottom of the threading finger 23 and will be located behind the post 27 as 40 shown in Fig. 3. As the shuttle continues to move to the right on the second pick after transfer the end of the filling T will be held by the selvage on the side of the loom opposite the transfer mechanism and the weft will therefore assume the position shown in Fig. 45 3, passing over the tubular element 30 and being caught by both horns 33 and 34. Because of the post 27 the tension in the warp due to the flight of the shuttle will draw the 50 light plunger 35 to the left or toward the bobbin against the action of the elastic 40 and as this occurs the filling extending between the horns will move up the inclined top surface of the arm 43 and eventually will slip 55 behind said arm 43 and be caught thereunder. When the shuttle arrives at the end of its right hand movement any slack which may occur in the filling will be taken up by the elastic 40, arm 37 moving to the right from 60 the position shown in Fig. 2 to that shown in Fig. 3 to draw the horns and plunger away from the arm 43. The thread of course being caught under the arm 43 and being held by the horns 33 and 34 will be given a sinuous form to take up a considerable length 65

of thread in a relatively small part of the shuttle. The block is provided with a delivery opening 60 which may be of any approved form such as shown in Figs. 3, 4 and 5 so that the filling will ordinarily assume 70 the position shown in Fig. 3 when the shuttle is at rest. The spring 36 is shown as a convenient means for establishing flexible connection between the lever 37 and the plunger 35, but I do not wish to be limited to the use 75 of a spring inasmuch as resilience in the connection between these two parts is not absolutely necessary. As clearly shown in Fig. 3 the strains placed on the plunger 35 by the horns 33 and 34 are operative on both sides of said 80 plunger and therefore there is little tendency for the latter to cramp or stick in the bore 31, movement of the plunger in the bore being free and unresisted because of the even distribution of the strains of said plunger due to 85 the fact that the horns are located on opposite sides thereof.

From the foregoing it will be seen that I have provided a simple shuttle wherein thread engaging horns on opposite sides of 90 the plunger cooperate with a fixed arm so that movement of the plunger under influence of the elastic 40 will tension the weft and take up any slack which may occur therein. It will further be seen that by having the horns 95 33 and 34 to extend on opposite sides of the plunger the latter is relieved of lateral or twisting strains and is free to move with a minimum of resistance in the bore 41.

Having thus described my invention it will 100 be seen that changes and modifications may be made therein by those skilled in the art without departing from the spirit and scope of the invention and I do not wish to be limited to the details herein disclosed, but what 105 I claim is:

1. In a shuttle having a longitudinally extending thread passage and a delivery eye located in the front wall thereof, means defining a tube located between the delivery eye 110 and the thread passage, a plunger movable in the tube, a pair of thread engaging horns carried by and extending on opposite sides of the plunger and projecting through the tube, a fixed inclined thread engaging arm, said 115 horns being inclined in a direction opposite to the inclination of the fixed arm, the thread extending around the horn and threading arm, and means to cause relative movement between the plunger and the fixed arm to 120 tension the weft and take up any slack which may occur therein.

2. In a shuttle having a longitudinally extending thread passage and a delivery eye located in the front wall thereof, a plunger guided in the shuttle for movement in a direction substantially parallel to the length of the shuttle, a pair of horns mounted on opposite sides of the plunger inclined upwardly and toward the adjacent end of the shuttle, 125 130

- a fixed thread engaging arm inclined upwardly and toward the center of the shuttle, said horns and arm being between the thread passage and the delivery eye, the thread extending around the horn and threading arm and means to cause movement of the plunger and horns away from the fixed arm to tension the weft and take up any slack which may occur therein.
- 5 3. In a shuttle having a longitudinally extending thread passage and a delivery eye located in the front wall thereof, a plunger guided for movement in the direction of the length of the shuttle and located between the thread passage and the delivery eye, a pair of spaced horns extending on opposite sides of the plunger and secured to the latter, said horns being inclined upwardly and toward the adjacent end of the shuttle, a threading arm located intermediate the horns and extending upwardly and toward the center of the shuttle, and means tending normally to hold the plunger and the horns away from the threading arm, the filling extending from
- the bobbin as it extends from the threaded 25 position to the delivery eye moving the horns and plunger toward the threading arm and being moved up the latter to be engaged and held thereby as the resilient means moves the plunger away from the bobbin.
- 30 4. In a shuttle having a longitudinally extending thread passage and a delivery eye, a plunger mounted for movement in the shuttle in a direction substantially parallel to the length of the shuttle and located between the 35 thread passage and the delivery eye, a horn extending from the plunger and inclined upwardly and toward the adjacent end of the shuttle, a threading arm inclined upwardly and toward the center of the shuttle, and fixed relatively to the shuttle, the thread extending from the thread passage around the horn and threading arm and toward the delivery eye, and resilient means to move said plunger and horn away from the arm.
- 40 45 In testimony whereof I have hereunto affixed my signature.

ALBERT CEDERLUND.
